IMPROVEMENT IN RAILROAD RAILS.

JOSEPH ADAMS, OF FAIRHAVEN, VERMONT.

Letters Patent No. 60,112, dated December 4, 1866.

The Schedule referred to in these Letters Patent and making part of the same.

TO ALL WHOM IT MAY CONCERN:

Be it known that I, JOSEPH ADAMS, of Fairhaven, in the county of Rutland, and State of Vermont, have invented a new and useful Improvement in Railroad Rails; and I do hereby declare the following to be a full, clear, and exact description of the nature, construction, and operation of the same, reference being had to the accompanying drawings, which are made a part of this specification, and in which—

Figure 1 is a perspective view of a portion of a rail illustrating my invention.

Figure 2 is a transverse section of the rail when its two constituent parts are joined together; and

Figure 3 is a transverse section of the rail with its two parts disjoined.

Similar letters of reference indicate corresponding parts in the several figures.

This invention relates to an iron rail made in two parts or pieces, joined together longitudinally by a tongue and groove, and securely fastened together by transverse bolts.

The invention consists in rounding the top of each part or half of the rail, so as to form on each rail a central longitudinal crease or groove, in order to bring the pressure of the car-wheels directly over the center of the neck of each part of the rail and prevent the car-wheels from breaking off the contiguous edges.

In order that others skilled in the art to which my invention appertains may be enabled to fully understand and use the same, I will proceed to describe it in detail in connection with the accompanying drawings.

I construct my rail in two pieces or half-rails, A A', each rail being put down on the bed of the roadlapping the half rails past one another, like other continuous rails, as represented in fig. 1. The two half rails are joined together longitudinally by a tongue, a', on the part A', and a groove, a, on the part A. This tongue and groove connection prevents the parts or half rails from working up at the ends and becoming uneven, as a common T rail often does; and it also keeps the parts in their places, so that they shall not rise one above the other throughout the whole length of the rail. The top of the rail is of the form shown clearly at b b, fig. each of the parts, A A', being rounded off at the top so as to leave a central longitudinal groove or crease. The half rails are thus made highest at the points where the wheels will bear directly over the centre of the neck of each half rail, which prevents the latter from being spread apart or broken at their contiguous edges. The two parts A A' of the rail are securely fastened together by the transverse bolts D.

Having thus described my invention, the following is what I claim as new herein, and desire to secure by Letters Patent—

I claim a railroad rail made in two parts, A A', with their top surfaces so shaped as to form a central longitudinal groove c, and having said top surfaces highest at the points where the wheels will bear directly over the centre of the neck of each half rail, the whole being arranged and constructed substantially in the manner and for the purpose set forth.
